UNITED STATES PATENT OFFICE

THEODORE M. BRUBACK, OF DU BOIS, PENNSYLVANIA

SOOT CLEANER FOR BOILERS

Application filed December 20, 1927. Serial No. 241,291.

This invention relates to soot cleaners for boilers, and aims to provide certain improvements therein.

In this type of apparatus it is customary to introduce into the boiler at various points a series of cleaner elements, each comprising a pipe extending across the banks of tubes, the pipe being provided with nozzles through which steam is admitted to the boiler to clean the tubes, and the cleaner elements being provided with means for rotating them through an arc of a circle in order that the jets may sweep as many tubes as desired. Means are usually provided for opening and closing the valve which controls the flow of steam to the cleaner elements and in certain types of apparatus the cleaner element is rotated by the same mechanism which opens and closes the valve.

My invention relates to a device of this type in which the steam valve is in the nature of a poppet valve, that is to say, one which moves axially toward and from its seat. In other devices of this character the valve is seated by a spring and unseated by a cam, with the result that foreign matter lodges on the seat and is apt to produce leakage, since the power of the spring is not sufficient to crush such foreign matter. According to my invention the valve is closed under screw pressure, so that a powerful force can be directed against the valve seat by the valve, thus destroying any particles of matter which may become lodged on the seat and insuring a tight valve under all conditions. According to the present invention in its preferred form the cleaner is turned by the valve-operating mechanism with the result that the initial movement of the driving member (which is usually operated by hand) opens the valve and continued movements in the same direction rotate the cleaner. In the preferred form the valve rapidly arrives at its fully open position, and continues to move away from its seat with an

idle movement, during which the cleaner is operative. The invention includes other features of construction which will be herein-after more fully described.

Referring to the drawings which show several forms of the invention,—

Figure 1 is a longitudinal section of one form of the device.

Fig. 2 is a cross-section on the line 2—2 in Fig. 1.

Fig. 3 is a cross-section on the line 3—3 in Fig. 1.

Fig. 4 is a cross-section on the line 4—4 in Fig. 1.

Fig. 5 is a longitudinal section of another form of the invention.

Referring to the drawings, let A indicate the usual boiler setting having an opening which is lined by a box B. Extending through this opening is a tubular member C which may be considered as a part of the cleaner element. Projecting toward the right from the element C is a screw-threaded sleeve D forming a continuation of the cleaner element and screwed on the sleeve D is a nipple E to which is attached with a leak-tight joint an extension piece F which turns with the element. To the nipple E is attached a valve seat G which is controlled by a valve H mounted upon a valve stem I. The valve H is of the poppet type and is opened and closed by rectilinear motion imparted to it through the stem I.

The valve stem I is operated by any suitable driving means (preferably hand-actuated), such as the sheave wheel J shown, the latter being connected with a screw-threaded sleeve or nut K, so that when the wheel is turned by a chain or the like the sleeve is also turned, thereby moving the stem backward and forward and opening and closing the valve.

The valve is so proportioned and constructed that a small movement away from its seat will admit sufficient steam to the cleaner to effectively clean the boiler, so that

shortly after the rotation of the sheave is begun, the valve will be in wide open position. According to the preferred form of the invention, the valve continues to move away from its seat until the cleaner has reached the end of its forward turning movement, whereupon the valve begins to move toward its seat, which movement is continued until the cleaner approaches close to its initial position, whereupon the valve becomes effective to close the steam passage.

In order that when the sheave is turned the valve stem I shall not turn unduly with it, I provide the stem with a guide L which is shown as having slots M engaging guide-ways N fixedly secured to the extension F. By this means while the stem I may rotate slightly because of the movement of the extension, nevertheless such movement is negligible so far as proper operation of the valve is concerned. Other means may be employed for preventing undue rotary movement of the stem if desired. It is preferred to swivel the valve H to the stem I, so that any slight rotary movement of the stem need not be transmitted to the valve. This is shown as accomplished in the present construction by means of a flange O on the stem which is engaged by a collar P on the valve, the parts being somewhat loosely connected and permitting swivelling while still holding the valve on the stem.

Steam may be led to the interior of the extension F, through a steam chamber Q, fed by a steam pipe R, as best seen in Fig. 1. A suitable stuffing box S is provided to prevent leakage around the exterior of the extension F where it enters the chamber Q.

Since in the preferred form of the valve-operating device continues to open the valve during the turning movement of the cleaner which is to be described, the movement of the stem may be used as a stop means for limiting the rotation of the cleaner. This is very simply accomplished in the present construction by the introduction of a sleeve T which may be of any length suited to the individual installation. When the guide L on the outward movement of the valve strikes the sleeve T (which bears against a wall on the chamber Q) further rotation of the sheave is prevented and consequently further rotation of the cleaner element is also stopped. The direction of pull on the sheave is then reversed, so that the latter turns in an opposite direction until the valve again meets its seat. A suitable stuffing box I' is provided to prevent leakage from the chamber Q around the stem I.

As before stated, in the invention in its preferred form the valve-operating mechanism also operates to turn the cleaner element. This result is accomplished by means of a gear train connecting the screw-threaded sleeve K with the nipple D. As shown, such

train comprises a pinion U mounted upon the screw-threaded sleeve K which meshes with a gear V carried upon one end of a shaft W, which shaft at its opposite end is formed with gear teeth to constitute a pinion X which meshes with a gear Y fixed to the part D. The proportions of the gears constituting the gear train are such that it will require a number of revolutions of the sheave wheel to produce a single rotation of the cleaner element C. The actual number of revolutions required will depend upon individual installations, but an average ratio of 17 or 18 to 1 between the sheave wheel and the cleaner element secures satisfactory results.

In operation when the sheave wheel is turned to the left one or two turns, the valve is opened sufficiently to admit a substantially full head of steam. During this time the cleaner is rotating slightly and when the valve is opened takes up its effective operation of cleaning the tubes. Continued turning of the sheave wheel to the left results in a further opening of the valve which, however, is an idle movement while the cleaner element is passing through its arc of effective cleaning, and this continues until the guide L engages the sleeve T, whereupon further movement is prevented. The sheave wheel is then turned to the right, the valve moving toward its closed position and the cleaner element reversing its direction of movement, the return sweep of the cleaner element being effective for cleaning purposes until the valve has approached close to its seat, whereupon the full head of steam is cut down quickly until the valve is closed. The action of the valve is positive and it may be closed with any force required so that if dirt or rust lodges on the valve seat, it may be crushed by the valve and a tight joint always made. The movements of the various parts are simple and positive, since there are no catches or other operating devices involved in the system. During the intervals between operations the valve will, of course, be left in its closed position.

The invention also includes certain details of construction which will now be described: The cleaner element is supported near its end in a spring bearing A' which engages the outer side of the sleeve D. The bearing is supported by springs B' with its lateral face C' making close contact with a face E' of a plate F' bolted to the lining B. This provides a spring mounting for the cleaner element which is substantially air tight and which permits automatic adjustment of the cleaner with relation to the boiler casing as the latter may be affected by expansion or contraction.

A ball bearing G' is preferably introduced between the nipple E and a plate H' so as to assist in the easy turning of the cleaner element. The plate H' serves as a partial hous-

ing for the gear Y, the housing being completed by a thin plate I' which is screwed to the plate H'. The plates H' and I' are so constructed as to also house the pinion X.

The steam chamber Q is bolted to the plate H' by several bolts J' J' while the opposite side of the chamber Q is provided with an extension K' which may be integral with a plate L' which serves as a bearing for the shaft W and also assists in enclosing the gears U and V. The housing for these gears is completed by a plate M' fastened to the plate L' by bolts N'.

By the construction just described all of the gearing is enclosed and protected while at the same time it is easily accessible for inspection and possible repairs.

In Fig. 5 I have illustrated a modification of my invention in which the sheave wheel A² is fixed on the valve stem B² which latter carries a screw C² operating in a nut portion D² of a bracket E². The valve stem passes through a stuffing box F² into a steam chamber G² and carries a valve H² which is preferably swivelled to the stem. The valve hence opens and closes by turning the sheave wheel, the valve arriving at its effective open position in one or two turns. Motion is communicated to the cleaner by means of a pinion I² fixed to the stem B² which engages a gear J² which has a broad face so that the pinion I² which moves backward and forward with the valve stem will always engage the gear. The gear is mounted on a shaft K² mounted at one end in a bearing in the bracket E², and near the other end in a bracket L². The shaft carries at its extreme end a pinion M² meshing with a gear N² which is mounted upon an extension O² of the cleaner P². The extension O² leads through a stuffing box Q² into an auxiliary steam chamber R² which is connected to the main steam chamber G² by oblique pipe S². The auxiliary steam chamber is bolted to the bracket L² by bolts T².

The operation of this modification of my invention is substantially that of the form first described, namely, the sheave wheel is rotated in one direction to open the valve and upon a continuance of the rotation in the same direction the cleaner element is rotated by means of the gear train until the end of the desired arc of travel has been reached, whereupon the rotation of the sheave wheel is reversed, the valve moving toward its seat as the cleaner element turns toward its initial position and reaching its seat shortly after the end of the operative rotation of the cleaner. Various forms of stop device may be arranged to limit the arc, such as the stop U² arranged on the gear N² which engages a suitable abutment (not shown) when the desired amount of travel has been reached.

In constructing either of the devices herein described the proportions are preferably so arranged as to provide a maximum rotation

of the cleaner element equal to substantially 360°. This is seldom required, however, but any smaller degree of rotation can be effected by the stops referred to.

While I have shown and described several forms of the invention, it will be understood that I do not wish to be limited thereto, since various changes may be made therein without departing from the spirit of the invention.

What I claim is:

1. In a boiler cleaner, a cleaner element, means for rotating the element, a separate rectilinearly moving valve for controlling the supply of steam to said element, a long screw-threaded stem for said valve, and a nut engaging said stem, one of said last-named parts being rotated at all times while the element is rotating, and moving the valve in its opening movement a much greater distance than is necessary to supply the element with the required amount of steam, whereby to create a period of operative supply of steam during the angular movements of the element to and from its extreme operative position, the parts being constructed to give the valve a continuous idle movement beyond its effective opening and closing movements and to close the valve positively.

2. The boiler cleaner of claim 1, in which the valve seat opening is in the direction of extension of the cleaner, whereby the operative mechanism may be kept in line with the cleaner.

3. The boiler cleaner of claim 1, in which the valve seat opening is in the direction of extension of the cleaner and is mounted directly at the end of the cleaner.

4. The boiler cleaner of claim 1, in which the valve has a long screw threaded stem and a rotatable nut for operating it, the valve stem being sufficiently fixed against rotation to enforce a longitudinal movement of the valve stem when the nut is rotated.

5. The boiler cleaner of claim 1, in which the valve is mounted rotatively upon a screw threaded stem, and the stem is substantially fixed against rotation, a nut being provided to move the stem longitudinally.

6. In a boiler cleaner the combination of a cleaner element, a valve for controlling the passage of steam to said cleaner element, means for turning said cleaner element, a single means for opening and closing said valve and operating said turning means, and a stop device operating to limit the opening movement of said valve whereby to determine the arc of rotation of said cleaner element, said stop device comprising a sleeve independent of the valve-moving means, and removably associated with said valve whereby different arcs of turning may be obtained by varying the length of said sleeve.

7. In a boiler cleaner the combination of a cleaner element having an extension, a plate arranged near the end of the cleaner element,

5 a steam chamber connected to said plate, a second plate connected to said steam chamber and forming a bearing for a threaded valve stem, a valve on said stem within said extension, a valve seat also within said extension controlled by said valve, a threaded nut engaging said stem, means for turning said threaded nut to open and close the valve, and said threaded nut being connected by a gear
10 train to said cleaner element, and adapted to turn said element during the opening and closing of the valve.

15 8. In a boiler cleaner the combination of a cleaner element having an extension provided with a valve seat, a plate arranged near the end of the cleaner element, a steam chamber connected to said plate, a second plate connected to said steam chamber and forming a bearing for a threaded valve stem, a valve
20 on said stem within said extension, a valve seat also within said extension controlled by said valve, a threaded nut engaging said stem, means for turning said threaded nut to open and close the valve, and said threaded
25 nut being connected by a gear train to said cleaner element and adapted to turn said element during opening and closing of the valve, and discs fixed to said plates and enclosing the gears in said gear train.

30 9. In a boiler cleaner the combination of a cleaner element having an extension, a valve in said extension, a valve stem carrying said valve, a steam chamber into which said extension projects, said valve stem having a
35 threaded portion outside of said steam chamber, a rotatable nut engaging said threaded portion, guides in said extension, a part carried by the valve stem and engaging said guides to prevent undue rotation of said valve stem, a sheave wheel for rotating said nut whereby to reciprocate the valve stem and valve, a pinion on said threaded nut, a gear rotated by said pinion, a shaft rotated by said gear, a plate forming a bearing for said
40 shaft, a pinion on the opposite end of said shaft, and a gear connected with said cleaner element and rotated by said last-named pinion.

45 10. In a boiler cleaner, the combination of a cleaner element, a valve for controlling passage of steam to the cleaner element, said valve having a stem mounted parallel with the axis of the cleaner element, a screw for moving said valve axially toward and from its seat, a sheave wheel for moving said screw, a pinion rotated by said sheave wheel, a shaft parallel with the cleaner element and having a gear continuously in mesh with said pinion, a second pinion on said shaft, continuously
50 in mesh with a gear on said cleaner element, and said valve having an idle movement after opening during which the element is rotated.

55 11. In a boiler cleaner, the combination of a cleaner element, a valve for controlling passage of steam to the cleaner element, said

valve having a stem mounted parallel with the axis of the cleaner element, a screw for moving said valve axially toward and from its seat, a sheave wheel for moving said screw, a pinion rotated by said sheave wheel, a shaft parallel with the cleaner element and having a gear continuously in mesh with said pinion, a second pinion on said shaft, continuously in mesh with a gear on said cleaner element, and said valve having an idle movement after opening during which the element is rotated, together with means for enclosing the several pinions.

60 In witness whereof, I have hereunto signed my name.
